(57) **CLAIM**

We claim the ornamental design for a tape measure, as shown and described.

DESCRIPTION

FIG. 1 is a perspective view of a tape measure embodying the invention;

FIG. 2 is a front view of the tape measure of FIG. 1;

FIG. 3 is a rear view of the tape measure of FIG. 1;

FIG. 4 is a right side view of the tape measure of FIG. 1;

FIG. 5 is a left side view of the tape measure of FIG. 1;

FIG. 6 is a top view of the tape measure of FIG. 1; and,

FIG. 7 is a bottom view of the tape measure of FIG. 1.

The elements shown in broken lines are included for the purpose of illustrating environment and form no part of the claimed design.
